(57) **CLAIM**

The ornamental design for a light emitting diode module, as shown and described.

DESCRIPTION

FIG. 1 is a perspective view of a light emitting diode module showing our new design;

FIG. 2 is a front view thereof, the rear view being a mirror image of the front view;

FIG. 3 is a right side view thereof, the left side view being a mirror image of the right side view;

FIG. 4 is a top view thereof; and,

FIG. 5 is a bottom view thereof.

1 Claim, 4 Drawing Sheets
